UNITED STATES PATENT OFFICE.

ALEXANDER RHODES, OF GRAND RAPIDS, MINNESOTA.

RIFLE-CARRIER.

1,248,012.

Specification of Letters Patent. Patented Nov. 27, 1917.

Application filed June 4, 1917. Serial No. 172,726.

To all whom it may concern:

Be it known that I, ALEXANDER RHODES, a citizen of the United States, residing at Grand Rapids, in the county of Itasca, State of Minnesota, have invented certain new and useful Improvements in Rifle-Carriers; and I do hereby declare the following to be a full, clear, and exact description of the invention, such as will enable others skilled in the art to which it appertains to make and use the same.

This invention relates to improvements in article carriers, and is directed more particularly to a rifle carrier adapted for use when marching, riding or at other times when the use of both hands is desired and yet it is essential or expedient that the rifle be at hand and in readiness for instant use.

An object of the present invention resides in the provision of a carrier of the above character which may be quickly and conveniently applied to and removed from its operative position on the shoulder, will occupy but little space, is of extremely simple and inexpensive construction and at the same time entirely efficient in use.

A further and important object of the invention is to provide such a construction as will hold the rifle on the shoulder of the user and in such position that it may be instantly grasped by the butt so that the rifle may be instantly disengaged from the carrier and thrown into position for action, when the butt of the rifle is forced rearwardly.

With the above and other objects of similar nature in view, the invention consists in the construction, combination and arrangement of parts, set forth in and falling within the scope of the appended claim.

In the drawing:—

Figure 1 is a side elevation of the carrier illustrating its use.

Fig. 2 is a front view thereof.

Fig. 3 is a vertical section taken on the line 3—3 of Fig. 2, and

Fig. 4 is a transverse section taken on the line 4—4 of Fig. 2.

Referring now more particularly to the accompanying drawing, the carrier is shown as consisting of an elongated plate 5 of rust proof metal of suitable gage that is curved

longitudinally at one end as shown at 6 to engage and conform to the shoulder of a person employing the same and be supported therefrom as shown most clearly in Fig. 1. To retain the plate against displacement on the shoulder there is attached at the upper or curved end of the plate an adjustable strap 7 which is adapted to pass downwardly at an angle across the back of the wearer and be secured to the belt or other portions of the garments. A second strap 8 is attached at 9 to the other or lower end of the plate 5 and adapted to pass diagonally across the chest and be also secured to the belt. This strap 8 is likewise adjustable as will be understood. Attached by rivets 10 or other suitable means to the front face of the plate 5 adjacent its curved end is a second plate 11 between which and the plate 5 are disposed and secured by rivets, upper and lower leaf springs 13, the ends of each of which project beyond the sides of said plate and are oppositely curved outwardly therefrom as shown at 14. Spaced rods 15 are secured to and extend longitudinally of the plate 11 and have hinged thereto as at 16 the inner ends of a pair of clamping elements 17, said elements extending between the opposite ends of the spring 13 and being yieldably held thereby in contacting clamping relation. The free end portions 18 of the clamping elements 17 are outwardly flared as shown to facilitate the introduction theretwixen of the firearm to be carried.

In use, the carrier is applied to the shoulder as shown in Fig. 1 and the straps 7 and 8 properly adjusted to hold it securely in position. When marching, riding or at other times when the unimpeded use of both hands is desired, the rifle, gun or other firearm is positioned with its barrel disposed between the elements 17, the latter being clamped firmly upon the barrel under the influence of the springs 13 so that the firearm will be rigidly held in place against swinging and accidental dislodgment.

What I claim is:

A rifle carrier comprising a hooked plate adapted for engagement upon the shoulder of a person, means for holding the plate against displacement, a second plate secured to the first plate and having bars secured

in spaced relation thereto, clamping members having hooked ends engaged about the bars respectively, and a spring passed between the plates and having its ends disposed respectively against the clamping members in position to hold them yieldably in clamping relation.

In testimony whereof, I affix my signature in the presence of two witnesses.

ALEXANDER RHODES.

Witnesses:
